UNITED STATES PATENT OFFICE.

HARRY C. WENGEL, OF BIRMINGHAM, AND JOHN B. MICHAEL, OF SELMA, ALABAMA.

VALVE-GRINDING MACHINE.

Application filed December 31, 1924. Serial No. 759,165.

To all whom it may concern:

Be it known that we, HARRY C. WENGEL and JOHN B. MICHAEL, citizens of the United States, residing at the city of Birmingham, county of Jefferson, and city of Selma, in the county of Dallas, respectively, and State of Alabama, have invented a new and useful Valve-Grinding Machine, of which the following is a specification, reference being had to the accompanying drawings and to the letters and figures of reference marked thereon.

This invention relates to a machine of the type that is adapted to be used for grinding valves, such as those commonly known as plug-cocks, the invention having reference more particularly to a grinding machine that is specially adapted for grinding the angle-cocks comprised in railway air-brake equipment.

An object of the invention is to provide an improved grinding machine of such construction as to be simple and inexpensive, to economically supply the requirements of small shops, while permitting the addition of grinding facilities at minimum cost for other shops having need of a multiple machine to do a relatively larger amount of grinding.

Another object is to provide a grinding machine which shall be so constructed as to be depended upon to grind the contact surfaces of plug valves and their casing or valve bodies accurately, and automatically after the machine is started for operation, an aim being to eliminate faulty grinding resulting in leaky valves when the grinding had to be done on machines not specially adapted to perform its operations with the accuracy required, in the finishing and re-grinding of plug-cocks used for cutting off the flow through air, steam, and water pipes.

A further object is to provide an improved grinding machine unit that shall be so constructed as to be adapted to be attached to a common work-bench for support, where dismantling and preparing the valves to be ground and also re-assembling the valves after the grinding operations may be carried on by one workman who can conveniently direct the grinding operations, an important object being to eliminate the cost attending the transferring of valves to a distant grinding machine and back to an assembling bench.

A still further object is to provide an improved grinding machine, of either single or independent multiple spindle type, which shall be adapted to be supported on either a work-bench or a wall shelf adjacent to a work-bench to save floor space which may be valuable for large machines, which improved machine shall be substantial and reliable, and durable and economical in use.

With the above-mentioned and other objects in view, the invention consists in a grinding machine unit adapted to have other similar units connected therewith and to be mounted on various supporting structures, each of the units being adapted to be stopped or started at will and being so constructed as to change the positions of a valve body relatively to its plug-valve when the latter is rotated; and, the invention consists also further in certain novel parts and combinations and arrangements of parts, as hereinafter particularly described and further more definitely defined and claimed.

Referring to the drawings,—Figure 1 is a side elevation of a grinding machine or one unit of a multiple machine; Fig. 2 is a vertical sectional elevation of the machine, partially broken away; Fig. 3 is a rear elevation of the machine; Fig. 4 is a top plan of Fig. 3; Fig. 5 is a fragmentary horizontal section approximately on the line V—V in Fig. 1; and Fig. 6 is a fragmentary elevation with parts in different positions relatively to Fig. 1.

Similar reference characters in the different figures of the drawings indicate corresponding elements or features of construction hereinafter referred to in detail.

In carrying out the objects of the invention any suitable or desired frame-work may be provided, but for the special purposes of the machine a flat frame plate 1 is preferred which has bolt holes 2 therein to permit the plate to be securely bolted to a work-bench 3. The frame plate preferably is integral with the middle portion of a cylindrical spindle housing 4 which is normally vertical and has a suitable bearing portion 5 on its top. A spindle 6 of improved construction is provided and suitably fitted to rotate in the housing 4, and it has a head portion 7 that extends out over the top of the housing for support and has a guard 8 that extends about the upper portion of the housing to exclude abrading substance from the hous- 110

ing interior, bearing balls 9 preferably being arranged upon the bearing portion 5 to directly support the spindle head. The spindle has a relatively small central stem 10 that 5 projects upward beyond the head portion and has an axial screw-threaded stud 11 thereon, to which the rotary member or plug of a valve or stop-cock may be secured to be rotated in grinding operations. The lower 10 end of the spindle has a shaft projection 12 thereon that is provided on its end with a detachable collar 13 which supports a bevel pinion 14 rotatably on the projection, with space between the pinion and the lower end 15 of the spindle housing. The hub of the pinion has clutch members 15, and a clutch sleeve or collar 16 is arranged on the shaft portion 12 between the housing 4 and the pinion and has clutch members 17 thereon to 20 engage the clutch members 15, the sleeve being slidable on the shaft portion and adapted to rotate the spindle by means of a spline 18 suitably arranged. The sleeve has a stop pin 19 fixed thereto to engage a 25 projection 20 that is fixed on the housing, for stopping rotation of the spindle when the sleeve is disconnected from the pinion. The sleeve has a circumferential groove 21 into which a shifter fork 22 extends, for 30 shifting the sleeve, the fork being supported on a pivot pin 23 with which a frame member 24 is provided, the latter being a part of the machine frame, and the fork has a suitable operating lever 25. The spindle 6 may 35 be sufficiently heavy to maintain its proper position but may be provided with a circumferential groove 26, and a guide stud 27 may be screwed in the wall of the housing 4 so as to extend into the groove to prevent the 40 spindle from being pulled upward in operation, or the spindle may be otherwise axially guided.

The pinion 14 is driven by means of a 45 bevel gear wheel or pinion 28 secured to a driving shaft 29 which is arranged below the pinion 14 and rotatably supported by suitable frame members such as hangers 30 and 31 secured to the frame plate 1, and the shaft 29 may be driven by any desired 50 means, as a belt pulley 32. The driving shaft may be of any suitable length sufficient to drive the spindles of other grinding units that may be comprised in a multiple machine.

55 A tripper shaft 33 is rotatively mounted also in the machine frame, preferably higher than the driving shaft and rearward of the spindle housing 4, being a suitable distance below the main frame plate 1, and the shaft 60 has a suitable tripper cam 34 fixed thereto. The shaft may be of sufficient length to comprise tripper portions of other units of a multiple machine. The shaft 33 has a gear wheel 35 secured thereto that is in 65 mesh with a gear wheel 36 which is secured

to the shaft 29, the gear wheels preferably being alike diametrically, but as it is desirable that the spindle and the tripper shaft rotate at different speeds, the pinion 14 should be either larger or smaller diametrically than the wheel 28 that drives it.

A tubular guide 37 is vertically secured in a suitable opening in the plate 1 and guides a tripper rod 38 above the cam 34 to be operated by the cam. The upper portion of the rod 38 preferably has a screw-threaded bore 39 therein receiving a screw-threaded rod extension 40, whereby the rod is rendered longitudinally extensible or contractible, the rod having a head 41 on its top and preferably having also a lock-nut 42 thereon engaging the top of the main part 38 of the tripper rod. The frame plate 1 has an arm or post 43 rigidly connected thereto and it supports a pivot bolt or pin 44 to which a tripper arm 45 is connected, the arm having a fork 46 on its end that is arranged above the head portion 7 of the spindle and straddles the stem or projection 10, whereby to periodically lift a valve body 49 while a plug-valve is being ground therein. A post 47 is suitably supported, preferably by the plate 1, and it extends upward adjacent to one side of the arm 45 and has a stop bar 48 on its top to be engaged by the 95 valve body, whereby rotation of the body is prevented.

In practical use, while the machine is at rest a plug-valve is secured to the projection 10, usually being screwed onto the stud 11, the plug-valve being in the form of a truncated cone, the tripper arm 45 is supported upon the head 41, flour of emery and oil or other abrading substance is applied to the surface of the plug-valve, and a valve body is placed on the plug-valve, after which the extension 40 may be adjusted to permit the fork 46 to clear the valve body, so as to permit the plug-valve to be properly ground in the valve body, the body being stopped against the finger 48, an angle-cock being shown by broken lines in Fig. 3 of the drawings to illustrate the above mentioned arrangement. Upon starting the machine, with the clutch sleeve 16 in connection with the clutch pinion 14, the spindle is rotated and consequently the grinding operations begin, the cam 34 forcing up the rod 38 and causing the arm 45 to be tripped up once upon each revolution of the tripper shaft 33, the fork 46 alternately pushing up and lowering the valve casing or body to insure thorough distribution of the abrading substance, which is necessary to prevent unequal grinding of the surfaces of the plug and its casing and preventing circumferential scratching of the surfaces, so that uniform and true grinding of the surfaces result. Since the rotary speed of the spindle may be either faster or slower than that of the shaft 33, depend- 130

ing upon the relative diameters of the pinions 14 and 28, the valve body as it is periodically lowered does not drop into contact with the plug-valve at the same point 5 in succession relatively to the rotary cycles, which would tend to cause slightly untrue surfaces, but the successive contacts are made at different points in the cycle of rotation of the plug-valve which insures the 10 most perfect fitting together of the contact surfaces of the valve and the casing or valve body. In operating a single unit the driving gearing may obviously be stopped at will to change the articles to be ground, but 15 in operating a machine having a plurality of units one man may attend to all the units and may stop either one of the units by means of the shifter lever 25 while permitting operation of the remaining units of the 20 machine, so that loss of time is reduced to the minimum. When the clutch sleeve 16 is disconnected from the clutch pinion 14 the sleeve is moved up to the bottom of the housing 4 and the stop pin 19 comes into 25 contact with the projection 20, causing stoppage of the spindle to prevent possible injury to the workmen while changing valves, and also preventing rotation of the spindle while the plug-valve is being screwed onto 30 or off of the stud 11, the drive shaft 29 continuing to rotate.

What is claimed as new is:

1. A valve-grinding machine unit comprising a hollow cylindrical housing vertically arranged and having a horizontal frame plate rigidly connected thereto for support, the frame plate being provided with frame members, a spindle rotatably mounted in the housing and having a device on its 40 top to rotatably carry a plug-valve, the spindle having a shaft portion on its lower end that projects beyond the housing, a bevel pinion rotatably connected with said shaft portion and having clutch members 45 thereon, a clutch sleeve slidably splined on said shaft portion between the housing and said pinion to engage said clutch members, means to control the sleeve, a drive shaft rotatably supported by the frame members 50 and extending under said pinion, a bevel drive wheel secured to the drive shaft in mesh with said pinion, a tripper shaft rotatably supported in the frame members and geared to the drive shaft, a cam secured to 55 the tripper shaft, a frame arm and a vertical guide supported by said frame plate, a tripper rod arranged in said guide to be operated by said cam, and a forked tripper arm pivoted to said frame arm and engaged by 60 said tripper rod to intermittently lift a valve body from contact with the plug-valve.

2. In a valve-grinding machine, the combination of a cylindrical housing having a frame plate on the middle portion thereof to vertically support the housing, the plate having bolt-holes therein to secure it in place, and a spindle rotatably arranged in the housing and having a head portion extending over the top thereof, the head portion being supported upon said top and having an annular flange thereon extending downward and about the upper portion of the housing, said head portion being adapted to rotatably carry a valve thereon, with drive 75 gearing having connection with the lower portion of the spindle.

3. In a valve-grinding machine, the combination of a vertical cylindrical housing having a projection on the outer side of the lower portion thereof, the housing being provided with a frame, a spindle arranged in the housing and rotatably supported thereby to carry a valve, the spindle having a shaft portion extending downwardly beyond the housing, a bevel clutch pinion rotatably mounted on said shaft portion and having a clutch device, a sleeve splined on said shaft portion and having a clutch member to engage said clutch device to rotate the spindle, 90 the sleeve having a stop pin thereon to engage said projection to stop the spindle, a shifter fork supported by said frame and controlling said sleeve, a drive shaft supported by said frame, and a bevel wheel secured to the drive shaft in mesh with said pinion.

4. In a valve-grinding machine, the combination of a vertical cylindrical housing having a frame plate on the exterior thereof, a spindle rotatably arranged in the housing and having a projection on its top to carry a valve, a drive shaft, a tripper shaft rotatably arranged below said plate and geared to the drive shaft, a cam secured to the tripper shaft, a tubular guide secured in the frame plate above the cam, a trip rod arranged in the tubular guide and supported on the cam to be operated thereby, the upper portion of the trip rod having an extension adjustably secured thereto, said extension having a head on its top, a frame arm supported on the frame plate, a tripper arm pivoted to the frame arm and supported upon said extension head to be controlled thereby, the tripper arm having a forked portion to control a casing on the valve, and gearing connecting the spindle with the drive shaft.

In testimony whereof, we affix our signatures on the 8th day of December 1924.

HARRY C. WENGEL.
JOHN B. MICHAEL.
